UNITED STATES PATENT OFFICE.

WILLIAM H. McNUTT, OF NEW YORK, N. Y., ASSIGNOR TO CARRIE EMMA OWEN, OF FRANKLIN, NEW YORK.

WRENCH.

1,142,111.

Specification of Letters Patent.

Patented June 8, 1915.

Application filed September 17, 1913. Serial No. 790,220.

To all whom it may concern:

Be known that I, WILLIAM H. McNUTT, a citizen of the United States, and resident of New York city, in the county of New York and State of New York, have invented certain new and useful Improvements in Wrenches, of which the following is a specification.

This invention has for its object to provide, in a sliding jaw tool such as a wrench or pipe cutter, improved means for effecting the automatic sliding movement of the jaws from the swinging of a handle; in which the construction and assemblage of the parts will be simple and efficient; and in which the construction of the parts will give a maximum amount of strength to withstand a great amount of pressure and strain from hand and continuous use.

20 A further object of the invention is to provide in the said form of a tool, a construction in which the sliding jaw member is pivotally connected with a swinging handle by a link that is pivoted at its ends respectively to the two said members by being merely inserted laterally into sockets in such members, and retained in operative position causing the swinging of the handle to reciprocate the jaw member, by the opposed walls of a slotted portion of the body of the wrench.

35 A further object of the invention is to provide in the form of wrench above set forth, wherein a sliding jaw member is operated from a swinging handle by a connecting link, a form of abutment wall on the body member adapted to engage a portion of the handle, for the purpose of receiving the thrust imparted to the link when the jaw member is closed under pressure on a nut or other object, wherein the strain on the pivot of the swinging handle will be removed or lessened.

40 In the accompanying drawing illustrating embodiments of my invention: Figure 1 shows the tool in elevation, in open position. Fig. 2 shows the device closed on a nut, being a section of the line 2—2 as indicated in Fig. 4. Fig. 3 shows the body member in elevation. Fig. 4 shows the body member in end view. Fig. 5 shows a piece connecting the side walls of the slot in the body member. Fig. 6 shows a block secured in the slot in the body member, forming an abutment wall 55 for the handle. Fig. 7 shows in elevation

the jaw member. Fig. 8 is an end elevation of the jaw member. Fig. 9 shows the link. Fig. 10 shows the device as set forth in the aforesaid views, with cutting wheels or disks for use as a pipe cutter; and Fig. 60 11 is an end view of the device as set forth in Fig. 2, with the addition of cutting blades to the jaw members respectively, to constitute shears.

As shown in Figs. 1-9, the device comprises essentially a body member denoted generally by 12, a jaw member 13, slideable in the body member, a handle member 14 that is movably connected with the body member, as by a pivot, and a link 15, that 65 operably connects the handle with the jaw member to reciprocate the jaw member on the body as the handle is swung; and the jaw member and also the handle and the link are each as shown a single integral 70 structure; while the body member is composed of a slotted plate having at two opposite portions a small plate or block connecting the opposite walls of the slot and permanently secured in such position, forming a unitary structure without movable parts in itself. 80

The body member 12 comprises a main portion 16 having an extension 17 at one corner that constitutes one of the jaws of the 85 device; while the said main portion 16 is provided with a slot made throughout the interior of the main portion, thereby forming opposed walls 18 and 19 that are connected integrally only by the jaw 17, as 90 indicated in Figs. 3 and 4. These opposed walls 18 and 19 are connected at the two lower corners by blocks 20 and 21 respectively, that may be secured in place by rivets or other means. 95

The jaw member 13 is shown as composed of a shank portion 22 having a jaw portion 23 projecting from the upper edge at one end of the shank, and of a width corresponding to the jaw 17 of the body member; 100 while the shank portion 22 is of less width, being of a thickness to slide in the slot 24 formed by the two walls 18 and 19 of the body member.

The upper edge 25 of the shank 22 will 105 engage the wall of the slot 24 formed by the jaw portion 17; while the opposite edge 26 of the shank 22 will be guided by the edge 27 of the block 20, in the slot 24 in the bottom. The shank 22 in the end opposite to 110

that containing the jaw 23 has an extension or lug 28 on the lower side, and this portion is guided by the wall 29 formed by the piece 21 that is secured in the slot 21 in the body. By these means the jaw member 21 is slid able in the body member to move its jaw portion 23 to and from the jaw 17 of the body member.

The handle 14 is shown as having its end inserted in the slot 24 and is movably connected with the body member, preferably by means of a pin 30 passing through the two walls 18 and 19 of the body member, and through an aperture 31 in the handle, by which means the handle is pivoted on the body member.

The sliding jaw member is connected with the pivoted handle member by means of a link, that is pivoted at its ends respectively to these two members, whereby the swinging of the handle from the position in which the parts are shown in Fig. 1, to the position indicated in Fig. 2, will cause the jaw member 13 to slide on the body member, and bring the jaw 23 of the jaw member nearer to the jaw 17 of the body member.

In the construction illustrated the link 15 is shown as having a head 33 at one end of circular shape, and also a circular head 34 at the other end. The jaw member 13 is shown as provided with a slot 35 that is of circular shape, and located at the portion of the lower edge 26 that joins the lug 28, this slot being somewhat larger than a semi-circle, and of a size to have the head 34 inserted therein by a movement lateral to the two members; and the link being of the same thickness as the shank 22 of the jaw member, to fit in the slot 24 of the body member, the walls 18 and 19 of the body member will serve to hold the link in operative connection with the jaw members; it being permitted to swing a certain distance as will be understood by comparing Figs. 1 and 2, and the head cannot be withdrawn from the socket by any pull or thrust in the direction of the plane of the flat link.

The handle 14 is provided with a socket 36 formed of a circular curve to receive the head 33 on the link 15 as shown in Fig. 2, that will be retained in such position after its lateral insertion, by the walls 18 and 19 of the slotted portion 24 of the body member.

It will thus be seen that the link is pivotally connected with the jaw member and with the handle by integral means, and no additional members such as pins or screws are required; these three members, the handle, the link and the jaw member are first connected by inserting the two heads in their proper sockets, and then these members are inserted into the slot 24 of the body member before the blocks 20 and 21 (or 65 either one of them) has been secured in po-

sition: and then the pivot pin 30 is inserted to secure the handle in proper position, and these two blocks are secured in their proper position, whereupon the device is assembled in finished condition ready for use.

It will be understood by reference to Fig. 2, that pressure on the handle 14 in the direction of the arrow, will shift the jaw 23 from its position of Fig. 1 to that of Fig. 2 in which it is closed on a nut *n*, and continued pressure will cause the tool to turn the nut on a bolt *b* in the direction of the arrow on the nut; and it will be perceived that the movement imparted to the shank 22 of the jaw member, through the link 15, will be by 80 a thrust on the link, and not a pull; but the swinging of the handle in the opposite direction will cause a pull or tension on the link, which movement will open the jaws. But if it is desired to turn the nut in the opposite direction, then the wrench is reversed or turned upside down, that it will be readily seen, will cause the jaws to close on the nut and the link will still be subjected to a thrust pressure to turn the nut.

For the purpose of lessening or relieving the strain on the pivot pin 30, I provide an abutment wall arranged to engage the adjacent portion of the handle; and as shown the end of the handle 14 is provided with a curved edge 40 concentric with its axis of movement; and the block 20 is provided with a curved wall 41 also concentric to the axis of the pivot 30, and practically coincident with the curved wall 40; and when the handle is swung to the closed position indicated in Fig. 2 and pressure still applied, the described thrust on the link 15 will cause these curved walls 40 and 41 to engage and receive the thrust that would tend to shift the handle member on the body member, by either shearing the pivot pin, or enlarging its hole 31 in the handle end portion. If desired the pivot pin can have a slight amount of lateral movement 110 in its hole 31 in the handle to permit the said walls 40 and 41 to approach and recede, so that the handle will not bind in turning in the body member.

The construction of a tool with sliding jaws as has been described, is readily applicable to any form of a tool wherein two members carrying operating devices are brought to engage opposed portions of an object; and in Fig. 10 a construction identical with that described is shown, in which a jaw member 17' is provided with a pair of cutters 42 and 43, while the jaw 23' is provided with a single cutter 44, that are located similar to the cutters on a pipe 125 cutter.

When this tool is applied to a pipe or rod, and the handle swung to close the jaws, the three cutters will grip the pipe, and as the device is swung to move it around the 130

pipe, the pressure on the handle will constantly move the cutter 44 toward the opposed cutters 42 and 43, and as fast as the cutters sink into the pipe or rod, the pressure on the handle will advance them, causing them to feed in under a continuous pressure.

In Fig. 11 another form of tool is shown in which the jaws 17" and 23" are provided with cutting blades 45 and 46 respectively, that will obviously be caused to approach when closed on an object, and pressure on the handle tending to swing the tool around the object, will cause a continuous pressure on the two blades that will feed them into the article as fast as a channel is formed therein.

Having thus described my invention, what I claim is:

A wrench of the character described comprising a body portion carrying an integral jaw, said jaw projecting forwardly beyond the plane of the body portion and having a flat under face along said forwardly projecting portion to constitute a guiding surface, a block projecting beyond the surface of said body portion in the same direction as said jaw and diagonally opposite said jaw, said block having a flat upper face

constituting a guiding surface, a jaw carrying slide mounted to move transversely of said head and disposed between said guiding surfaces, a handle, means for pivoting said handle to said head upon the same side of said head as that upon which the slide lies, one edge of said handle above said pivot being provided with a socket, and the opposite edge of said handle above said pivot being formed upon the arc of a circle concentric with said pivot, that portion of the block adjacent said arcuate surface of the handle conforming to the curvature of the surface and lying in close contact therewith throughout, a pressure link having rounded ends, one of which is seated in said socket of the handle and said slide being provided with a socket which receives the opposite rounded end of the pressure link, the contact of the curved surface of the handle with the correspondingly shaped surface of the block serving to relieve the pivot of strain where the jaws come to a position of rest in grasping an object.

WILLIAM H. McNUTT.
